[57] CLAIM

The ornamental design for a vehicle tire, as shown and described.

DESCRIPTION

FIG. 1 is an end elevational view of a vehicle tire showing our new design;

FIG. 2 is a side elevational view thereof;

FIG. 3 is a perspective view thereof;

FIG. 4 is an enlarged fragmentary developed plan view of the tread design thereof; and

FIG. 5 is an enlarged cross sectional view thereof taken along the line 5—5 in FIG. 4.

It is to be understood that the tread design is repeated throughout the circumference of the tire, and the opposite side is the same as that shown.
